(57) **CLAIM**

The ornamental design for a compressor, as shown and described.

DESCRIPTION

FIG. 1 is a perspective view of a compressor on the front and right hand side according to a first embodiment;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is an end view of FIG. 1 from the left hand side;

FIG. 7 is an end view of FIG. 1 from the right hand side;

FIG. 8 is a perspective view of a compressor on the front and right hand side according to a second embodiment;

FIG. 9 is a front view of FIG. 8;

FIG. 10 is a rear view of FIG. 8;

FIG. 11 is a top view of FIG. 8;

FIG. 12 is a bottom view of FIG. 8;

FIG. 13 is an end view of FIG. 8 from the left hand side; and,

FIG. 14 is an end view of FIG. 8 from the right hand side.

FIGS. 8-14 are executed in grayscale. Grayscale shading is used to illustrate surface contour and does not represent any particular color.

The broken lines and ghosted regions in the drawings depict portions of the compressor that form no part of the claimed design.

1 Claim, 14 Drawing Sheets
